UNITED STATES PATENT OFFICE.

THOMAS J. GORMAN, OF NEW YORK, N. Y.

IMPROVEMENT IN SAMPLE-ENVELOPES.

Specification forming part of Letters Patent No. 222,394, dated December 9, 1879; application filed October 15, 1879.

To all whom it may concern:

Be it known that I, THOMAS J. GORMAN, of New York city, have invented certain new useful Improvements in Openable or Mailing Envelopes, of which the following is a specification.

My invention aims to provide an improved form of openable envelope for mailing purposes, which, while being of a simple and inexpensive construction, may be easily opened for an examination of its contents, and readily and securely closed after inspection; and the main feature of my invention may be stated to consist in constructing an envelope with a metallic pronged fastening embodied in its sealing-face, and adapted to be passed through a re-enforced or eyeleted opening in the flap and clinched or bent down upon the same to hold the flap securely closed in a readily-openable manner.

Figure 1 in the annexed drawings presents an elevation of the sealing-face of my improved envelope, and Fig. 2 a cross-section on X X.

The envelope, as illustrated, is made in any of the approved forms, preferably of strong Manila paper and in an oblong shape, with the flaps at the ends.

One end of the envelope is left open to receive the samples or other mailable matter, the flap *a* at this end being gummed on the margin, in the usual manner, so that the flap may be moistened and sealed down after the envelope is filled. The flap *b* at the other end, however, is, according to my invention, held down by a metallic fastening embedded in that end of the envelope. This fastening is indicated at *A*, and is preferably an ordinary form of paper-fastener made of soft brass, which is embedded in the sealing-face of the envelope under the flap *b*, with its bendable prongs or nibs projecting from the sealing-face, and adapted to pass through the flap and hold the same closed. This fastening is preferably formed with two bendable prongs or nibs, bendable in opposite directions; but a fastening with one or more nibs may be adopted without objection.

The fastening is held securely in the sealing-face of the envelope by socketing its headed end between the cemented overlying and underlying folds in the face of the envelope, as shown clearly in Fig. 2, thus forming a very secure yet simple means of holding the fastening, which prevents its becoming displaced either inwardly or outwardly from the envelope.

The flap *b* is perforated with a hole, *c*, to admit the prongs of the fastener *A* through the same when the flap is fastened down, and this opening is preferably re-enforced by several folds on the under side of the flap, or by a metallic eyelet, *B*, riveted in the opening, as illustrated in Fig. 1. The eyelet *B* thus greatly strengthens the sides of the hole and enables it to effectually resist the lateral strain thereon caused by bending the nibs, which would otherwise be liable to tear the flap.

It will now be seen that when the nibs of the fastener are passed through the eyelet of the flap and flattened down upon the same, as shown in Fig. 1, the openable end of the envelope will be closed in a neat and secure manner, not liable to open by accident.

It will be observed, however, that the postal clerk or other person may open the envelope to inspect or remove its contents by simply bending up the nibs and lifting the flap, which may be effected with great ease and quickness, while the envelope can be again sealed with equal facility by reversing the action, thus presenting an important advantage over the ordinary mailing-envelope fastened with tapes, the tying and untying of which require appreciable care and time, and are, moreover, liable to become loose from hurried and imperfect tying.

What I claim as my invention is—

1. An openable mailing-envelope constructed with a metallic pronged fastening embodied in and projecting from its sealing-face, and adapted to be projected through the flap and flattened down upon the same, substantially as herein set forth.

2. An openable envelope constructed with

a metallic pronged fastening having its headed end fixed in the sealing-face of the envelope by embedment between the overlying and underlying folds in the cemented joint of the envelope, substantially as herein shown and described.

3. An openable envelope constructed with a metallic pronged and bendable fastening

fixed in its sealing-face, together with a flap provided with a re-enforced or eyeleted opening to engage the prongs of said fastening, substantially as described and shown.

THOMAS J. GORMAN.
